(57) CLAIM

The ornamental design for a hook for supporting a curtain, as shown and described.

DESCRIPTION

FIG. 1 is an isometric view of a hook for supporting a curtain showing the new design, shown with a curtain in phantom as environmental detail.

FIG. 2 is an isometric view of the hook for supporting a curtain of FIG. 1.

FIG. 3 is a front elevation view thereof, with the rear elevation view being identical.

FIG. 4 is a right side elevation view thereof, with the left side elevation view being identical.

FIG. 5 is a top plan view thereof.

FIG. 6 is a bottom plan view thereof.

FIG. 7 is an isometric view of a hook for supporting a curtain showing an alternative embodiment of the new design, with a curtain shown in phantom as environmental detail.

FIG. 8 is an isometric view of the hook for supporting a curtain of FIG. 7.

FIG. 9 is a front elevation view thereof, with the rear elevation view being identical.

FIG. 10 is a right side elevation view thereof, with the left side elevation view being identical.

FIG. 11 is a top plan view thereof; and,

FIG. 12 is a bottom plan view thereof.

The broken dot-dot-dash lines shown in the figures are for the purpose of illustrating environmental structure and form no part of the claimed design. Neither the portions shown in broken dot-dot-dash lines nor the broken dot-dot-dash lines themselves form any part of the claimed design.

The views are shown with a symbolic break in the length of the design that is represented with broken dot-dash lines. The appearance of any portion of the article between the break lines forms no part of the claimed design. The broken dot-dash lines themselves form no part of claimed design.
